Primary Examiner — David Muller*Assistant Examiner* — Nathan Johnston(74) *Attorney, Agent, or Firm* — Michael Best & Friedrich LLP(57) **CLAIM**

The ornamental design for a needleless syringe, as shown and described.

DESCRIPTION

FIG. 1 is a front, top, left perspective view of a needleless syringe showing my new design;

FIG. 2 is a rear, top, right perspective view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof; and,

FIG. 8 is a bottom plan view thereof.

The portions shown as broken lines are unclaimed portions of the needleless syringe and form no part of the claimed design.
